UNITED STATES PATENT OFFICE.

NELSON K. SMITH, OF DALLAS, TEXAS.

TONGS.

Application filed January 22, 1925. Serial No. 4,094.

This invention relates to new and useful improvements in tongs.

The object of the invention is to provide certain improvements upon the tongs set forth in my co-pending application filed February 12, 1924, Serial No. 692,204, as well as to add numerous advantageous features.

One of the improved features resides in the provision of a plurality of gripping faces on the inner surface of the yoke, each face being shaped to a different radius, whereby pipes of various diameters may be more efficiently gripped and the use of bushings is obviated.

Another improved feature is embodied in the gripping arm and its extension and consists in forming the face of the extension on a different arc from the arm and in such relation thereto, that the extension will adjust itself to smaller diameters; while the arm acts efficiently and positively on all sizes received by the yoke.

Among other improved features are a reversible latch; interchangeable handle levers; and a removable die and fastening therefor.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a perspective view of tongs made in accordance with my invention and open for engagement with the pipe.

Fig. 2 is a cross-sectional view taken on the line 2—2 of Fig. 3,

Fig. 3 is a plan view, portions being illustrated in section,

Fig. 4 is an enlarged fragmentary plan view showing the arcs of the gripping faces of the yoke.

Fig. 5 is a sectional detail of the die and its fastenings, and

Fig. 6 is a perspective view of the carriage type of handle lever.

In the drawings the numeral 10 designates an arcuate yoke which is preferably cast of metal and formed of cheek plates 11 connected by a web 12. The ends of the web terminate some distance short of the ends of the yoke, thus leaving said ends slotted or bifurcated. The yoke is formed at one end with super-posed ears 13 and at the op-

posite end with similar ears 14. Concentrically of the ears 13 is a pivot bolt 15 secured by a nut 16.

A handle lever 17 is pivoted on the bolt 15 and may be removed by taking out the bolt. Between the ears 13 is pivoted a swinging gripping arm 18 which is mounted on bolt 19 passing concentrically through said ears. The bolt is removably held by a nut 20. The free end of the arm swings between the ears 13, when the arm is closed. An extension 21 is provided on the end of the arm and extends inwardly from the pivot bolt 19 between cheek plates 11 of the yoke.

The yoke is substantially U-shaped as shown in the drawings, but this is subject to variation. On the free end of the arm is formed a boss 22 and contiguous to this boss is a recess 23. The handle lever 17 has a lug 24 extending from one side at its pivot end, adapted to engage over the boss and enter the recess to force the arm into gripping relation with the pipe. The ends of the boss and lug are rounded and the lever has a concaved seat 25 at the base of the lug. The rounded end of the boss is received in this seat when the lug enters the recess. It will be seen that the lever has ample bearing on the arm to positively force it into gripping relation with the pipe.

One of the important features of the invention resides in the gripping faces of the yoke. In Fig. 4 I have shown on an enlarged view the three arcuate gripping faces, A, B, and C, extending inward from the outer end of the yoke and each having a different radius merging into the associated face. The arc of the face A has the shortest radius and is designed for gripping the smallest diameters of pipe handled by the tongs. The face B is for the largest diameters and the face C is for intermediate diameters. This enables the same tongs to be used on couplings, tool joints and pipes of various diameters. The web 12 extends along the face B and a portion of the face A, the remainders of the faces being formed by the edges of the cheek plate 11. The gripping face D of the arm 18 is built up by bosses 26 on the upper and lower sides of the arm contiguous to said face. This face is formed on a different arc from the face E of the extension 21, the latter being cut back with relation to the face D. This enables the extension to adjust itself to the face A when small diameters are engaged

and this is an important feature of the invention.

The lever 17 has a hand hold 27 and the arm 18 also has a hand hold 28. These may be used by the workman in handling the tool and for opening the arm. The arm has an outwardly or radially directed handle member 29 formed integral therewith. This member has a looped hand grip 30 on its 10 outer end by which the member may be grasped and swung. A vertical slot 31 extends longitudinally of the member. A gravity plate latch 32 pivoted in the slot has a trip 33 extending through an opening 34 15 at the end of the slot, whereby the trip extends into the loop of the grip 30 and thus may be grasped by the fingers of the hand holding the grip 30.

The latch has two apertures 35, either of 20 which may be engaged on a pivot bolt 36, whereby the tongs may be inverted. The vertical swing of the latch is limited by the amplitude of the opening 34. A pair of stop lugs 37 are formed on the ears 13 in the 25 path of the latch. When the latch is dropped the lower lug 37 is in the path thereof and the arm cannot be swung open.

For fastening the handle lever 17 in an open position so that the lug 24 will be 30 clear of the throat of the yoke I mount a dog 38 in a recess 39 formed in the web 12. This dog is mounted on a pivot pin 40 and has a notch 41 adapted to receive a lug 42 on the inner end of the lever 17 when the latter 35 is swung to its open position, the closed position of the lever being shown in full lines in Fig. 3.

The dog is sustained in its normal position by a coiled spring 43 mounted in the recess 40 and tending to force the nose 44 of the dog from between the cheek plates into the path of the pipe. The dog has a dual function in that it not only fastens the lever, but acts to pull the yoke up to the pipe and to take 45 up play. The spring 43 is strong enough to exert considerable tension and when the nose 44 is depressed into the recess 39, the lip 45 is swung out against the pipe, thus tending to bring the yoke close to the pipe.

50 In the face D of the gripping arm 18 are mounted a pair of gripping dies 46 in dovetail slots 47 extending through the bosses 26. The dies preferably have diagonally disposed teeth upon their exposed surfaces. Each die is held in place by a spring-pressed plunger 48 (Fig. 5) mounted in a counter bore 49. The head of the plunger engages in a socket 50 in the back of the die; while the stem of the plunger extends from the outer face of 55 the arm. The plunger not only prevents vertical displacement of the die, but holds it snug in its slot; however the die should have a snug sliding fit in the slot. To remove the die the plunger 48 is pulled outwardly to withdraw its head from the socket

50, after which the die may be pushed from the slot.

It is to be understood that the tongs may be used either as a break-out tool, for engaging the members of a tool joint; or as 70 a back-up tool which is supported on a carriage on the rotary table. For supporting the tongs in a carriage a short handle lever 51 (Fig. 6) is substituted for the lever 17. The tongs are readily supported by a hanger 75 52 in which they may be easily balanced.

In using the tongs the latch 32 is lifted by 80 pressing down on the trip 33, then the arm 18 may be swung by means of the handle member 29 to the open position shown in Fig. 1. The handle lever 17 is also swung to its open position in which it is held by the engagement of the lug 42 in the notch 41 of the dog 38. When the tool is thus opened the 85 throat of the yoke is free to receive the pipe, the extension 21 being in the path thereof. The workman standing in front of the open yoke 10 grasps the hand hold 27 of the lever 17 with his right hand. He may also grasp the hand hold 28 with his left hand. He 90 then pulls or swings the yoke to the pipe. The extension 21 will engage the pipe and swing the arm 18 to a closed position.

The hand hold 28 may be omitted and 95 hand loop 30 grasped by the left hand of the workman. In this position the arm is swung by the workman through the agency of the handle member 29 and the extension 21 does not function as a closing element. 100 When the arm approaches its closed position the latch 32 rides past the lower stop 37, thus locking the arm in its closed position. As the yoke is pulled up to the pipe the nose 44 of the dog 38 is engaged by the 105 pipe and said dog swung on its pivot 40. This swings the lip 45 outward against the pipe with the result that the yoke is drawn up to the pipe until one of its faces, A, B or C engages therewith. The term 110 "pipe" as used herein includes the pipe proper, couplings and tool joints.

When the dog is swung or depressed its notch 41 is moved away from the lug 42, thus freeing the latter and permitting the lever 17 to be swung. The lever swings 115 freely until the boss 22 of the arm 18 is received in the seat 25 and the lug 24 enters the recess 23. The lever will now ride on the rounded surface boss, thus swinging the arm inward and forcing the dies 46 into the surface of the pipe. As the swing of the lever is continued the lug 24 will go deeper into the recess 23 and exert greater pressure upon the boss 22. When the dies engage the pipe there will be a slight circumferential movement of the yoke, but the teeth of the dies will bite into the pipe so quickly, that said movement will be of little consequence except to prevent crushing and assure a more 120 positive grip.

By observing Fig. 3 it will be seen that when the arm reaches its closed position the face E will recede from the face A of the yoke, thereby obviating interference, but leaving the face D of the arm free to function. The smaller diameters of pipe will readily seat against the face A and the yoke and arm will undergo a more pronounced circumferential movement, thus assuring a positive grip and preventing crushing. The larger diameters such as couplings and tool joints will seat against the faces B and C. By this arrangement the use of bushings to give the proper gripping faces is obviated and the tool may be instantly shifted from pipe sizes to couplings or tool joints without alteration or change of parts and with as effective action.

Sufficient amplitude is given the face D to co-act with the faces of the yoke in effectually gripping the pipe. The gripping action while positive and being free from undue slippage is mild to the extent of not flattening, crushing or denting the pipe. This is due to the fact that the gripping action is more tangential than radial.

Various changes in the size and shape of the different parts, as well as modifications and alterations may be made within the scope of the appended claims.

What I claim is:

1. A pipe tongs including, an integral yoke for receiving a pipe, a swinging gripping arm pivoted to the outer end of the yoke, an outwardly extending handle member on the pivoted end of the arm having a hand loop on its outer end, a latch pivoted in the handle member and having an operating element extending into the hand loop of the handle member, said latch co-acting with the yoke to hold the arm in its closed position, and a handle lever pivoted to the inner end of the yoke and engaging with the free end of the arm for gripping a pipe.

2. A pipe tongs including in combination, a substantially U-shaped yoke having a plurality of pipe gripping faces, each having a different radius, a swinging gripping arm pivoted at one end to one of the ends of the yoke, an extension projecting from the pivoted end of the arm into the end of the yoke, said arm having an arcuate face, gripping dies mounted in the face of the arm, a handle member extending radially from the

arm at its pivot and having a longitudinal slot, a hand loop on the outer end of the member, a latch pivoted in the slot of the member and having a trip extending into the hand loop, a boss on the free end of the arm contiguous to a recess in the arm, a handle lever pivoted to the other end of the yoke having a seat for receiving the boss of the arm, and a lug on the lever contiguous to the seat engaging in the recess of the arm.

3. A pipe tongs including in combination, a substantially U-shaped yoke having a plurality of pipe gripping faces, each having a different radius, a swinging gripping arm pivoted at one end to one of the ends of the yoke, an extension projecting from the pivoted end of the arm into the end of the yoke, said arm having an arcuate face, gripping dies mounted in the face of the arm, a handle member extending radially from the arm at its pivot and having a longitudinal slot, a hand loop on the outer end of the member, a latch pivoted in the slot of the member and having a trip extending into the hand loop, a boss on the free end of the arm contiguous to a recess in the arm, a handle lever pivoted to the other end of the yoke having a seat for receiving the boss of the arm, a lug on the lever contiguous to the seat engaging in the recess of the arm, a hand hold on the lever, a spring pressed element pivoted in the yoke disposed to engage an object within the yoke and having an operating face, and a lug on the inner end of the lever engaged by the face when the lever is swung to its open position.

4. A pipe tongs, including a rigid yoke having a plurality of individual arcuate gripping faces arranged in merging relation and formed of different radii, a swinging gripping arm pivoted to the outer end of the yoke, an outwardly extending handle member on the pivoted end of the arm having a hand loop on its outer end, a latch pivoted in the handle member and having an operating element extending into the hand loop of the handle member, said latch co-acting with the yoke to hold the arm in its closed position, and a handle lever pivoted to the inner end of the yoke and engaging with the free end of the arm for gripping a pipe.

In testimony whereof I affix my signature.

NELSON K. SMITH.
